Attorney.

UNITED STATES PATENT OFFICE.

GEORGES CLOETENS, OF BRUSSELS, BELGIUM.

MANDOLIN ATTACHMENT FOR PIANOS.

1,392,248.

Specification of Letters Patent. Patented Sept. 27, 1921.

Application filed March 7, 1921. Serial No. 450,499.

To all whom it may concern:

Be it known that I, GEORGES CLOETENS, manufacturer of organs at Brussels, Belgium, 37 Rue de Lauzanne, a subject of the 5 King of Belgium, have invented certain new and useful Improvements in Mandolin Attachments for Pianos; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

In stringed instruments played by means of hammers such as pianos, it has already been proposed to cover with a metal plate the whole of that portion of the hammer 20 which strikes the strings, in order to obtain a sound resembling that of a plucked string. Each time this effect must be obtained it is necessary to secure said metal fitting on each of the hammers.

25 According to the present invention, it is possible to do away with this drawback and besides to attain a more beautiful effect of plucked strings by the use of a hard piece, arranged permanently on the side of the 30 hammers and adapted to come into contact with the strings only when the hammers have been moved laterally.

Two embodiments of the invention are shown by way of example in the accompanying 35 drawings. Figure 1 is a side view and Fig. 2 a front view of a piano's hammer; Figs. 3 and 4 are end views of the hammer in two different positions.

Figs. 5 and 6 show respectively a side view 40 and a front view of the hammer according to a second embodiment of the invention.

According to the embodiment of Figs. 1 to 4, the hammer 1 with its felt head 2 is provided with a metal piece 3, screwed on 45 the body 4 of the hammer. The piece 3 is in the shape of a plate, the end of which is turned up so as to form a curved surface 5 arranged on the side of the head 2 and projecting beyond the surface of said head.

50 During the ordinary play of the instrument, the felt head 2 has with respect to the three strings I, II, and III corresponding to the note to be produced, the relative position shown in Fig. 3. When the player 55 acts on the "pianissimo pedal" (left hand

pedal) of the instrument, assuming a grand piano is being played, all the hammers move in the direction of the arrow X in Fig. 3, which movement has for its object, in an ordinary piano, to make the hammer strike 60 only two strings in the trebles, and only one string in the bass-notes. If the hammers are provided with the equipment according to the present invention, they take as a result of this movement the position shown 65 in Fig. 4, in which the metal surface 5 is opposite to one of the strings. Said surface projecting beyond the surface of head 2, this string I will be struck alone by the piece 5 and the two other strings II and 70 III only vibrate by sympathy, and by these means a beautiful effect of plucked string will be attained.

When it is required to adapt the invention to existing pianos in which there is 75 only a very small space between the hammers, it will be better to use the arrangement of Figs. 5 and 6. On the side of the felt head 2, in a portion of its surface which does not normally come into contact with 80 the strings, there is fixed a hard piece 6 provided with claws 7 which are forced into the felt. When the hammers are moved in the direction of the arrow X, (Fig. 6), the same result is attained as by the arrangement 85 previously described.

The hard pieces used according to the present invention can receive any suitable shape, either flat or curved. The movement of the hammers by means of the pianissimo 90 pedal of the instrument is pointed out only by way of example, for this movement could be produced by any other suitable means and that this movement could similarly be produced by movement in a direction contrary to that of the movement of the hammers when actuated by the pianissimo pedal. Thus the hard piece could also be arranged on the felt head between the portions of 95 said head which normally strike the strings, 100 so that said piece can pass between the strings during the ordinary play of the instrument.

What I claim is:

1. In a stringed instrument played by 105 means of hammers means for producing the effect of plucked strings comprising hard pieces fixed on a portion of the hammers which does not strike the strings during the ordinary play, and projecting beyond the 110

surface of the hammers, so as to strike one or more of the strings of each note when the hammers are moved laterally.

2. In a stringed instrument played by means of hammers the combination of a hammer, and a hard piece fixed on the hammer, said piece projecting beyond the surface of the hammer for striking one or more of the strings of the note when the hammer

is moved laterally, whereby the effect of 10 plucked strings is produced.

In testimony whereof I affix my signature in presence of two witnesses.

GEORGES CLOETENS.

Witnesses:

GEORGES VANDER HAHEYDEN,
LOMERID LEVER.
